UNITED STATES PATENT OFFICE.

JOHN HOWARD McELROY, OF CHICAGO, ILLINOIS.

LOCKED-SEAM-CAN-BODY MACHINE.

No. 818,109.

Specification of Letters Patent.

Patented April 17, 1906.

Application filed June 7, 1902. Serial No. 110,626.

To all whom it may concern:

Be it known that I, JOHN HOWARD McELROY, a citizen of the United States, residing at Chicago, in the county of Cook and State 5 of Illinois, have invented certain new and useful Improvements in Locked-Seam-Can-Body Machines, of which the following is a specification.

My invention is concerned with certain 10 new and useful improvements in locked-seam-can-body machines of the general type shown in my application Serial No. 101,838, filed April 7, 1902, and is designed to improve and simplify such machines, so as to 15 enable them to be operated at a higher rate of speed and with less internal friction, so that the output can be materially increased.

My invention is concerned with a mandrel, whether stationary or rotating, provided 20 with a longitudinal groove in which the seam is formed, together with a pair of tucking members adapted to coöperate therewith in sequence to form the seam. While it has been customary to employ a single blade or 25 rib as the tucking member to coöperate with the groove, I am, so far as I am aware, the first to employ a pair of blades or ribs with the advantage that by making the ribs of slightly different shape in cross - section 30 throughout their length, as shown, I am enabled to form a more perfect seam, and by omitting a portion of the edge of the second blade opposite the tongue I can use my invention to manufacture key-opening cans.

My invention is further concerned with a 35 novel automatic blank-feeding mechanism which I have shown as attached to and forming a part of my aforesaid lock-seaming machine, but which may be applied to any sort 40 of machine to which sheet blanks are fed.

My invention is finally concerned with certain novel combinations of elements and details of construction adapted for use in can-body machines, as will be fully described in 45 the following specification and specifically pointed out in the claims.

To illustrate my invention, I annex hereto four sheets of drawings, in which the same reference characters are used to designate 50 identical parts in all the figures, of which—

Figure 1 is a side elevation of a machine embodying my invention, with a portion of the horn and the attached soldering mechanism omitted. Fig. 2 is an end elevation of the 55 machine as it would appear in section on the line A A of Fig. 1. Fig. 3 is a top plan view

of the machine. Fig. 4 is a central longitudinal section on the line B B of Fig. 3. Fig. 5 is a detail in section on the line C C of Fig. 7. Fig. 6 is a detail of a portion of the machine 60 proper inside elevation with some of the framework removed and with the blank-feeding mechanism in section on the line D D of Fig. 2. Fig. 7 is a sectional view of a portion of the machine on the line E E of Fig. 1, but on 65 an enlarged scale. Fig. 8 is another detail on the same scale as Fig. 7 of a portion of the machine in end elevation and with the blank-feeding mechanism removed to show the blank-receiving recess in the machine. Figs. 70 9 and 10 are details in section on the lines F F and G G of Fig. 8. Fig. 11 is an enlarged detail in section on the line H H of Fig. 4, showing the parts in the position they are at when the first hook is just completed; and Fig. 12 75 is a similar view, but showing the parts in the position they assume when the second hook is completed and the can-body is ready to be discharged onto the horn.

The general design of the machine is the 80 same as that shown in my aforesaid application Serial No. 101,838, and the seam-pressing mechanism and mechanism for moving the can along the horn to be soldered is illustrated as being exactly the same as that 85 shown in the foregoing application; but it will be understood that other mechanism for these purposes might be substituted for those shown and employed in connection with the novel features of my invention. 90

The main portion of the framework of the machine consists of the base-plate 20, from which rise three pillars 21, 22, and 23, which are preferably connected by the top cross-piece 24. The power is applied to the heavy 95 belt-wheel 25, which is secured upon the sleeve 26, which has formed thereon the gear-pinion 27, which meshes with the gear-wheel 28. The sleeve 26 is mounted to rotate on the outer end of the shaft 29, which is journaled in the bearings 30 and 31, formed in the pillars 21 and 22, respectively, the sleeve 26 being secured in place between the shoulder 32, formed on the shaft 29, and the collar 33, secured to the end thereof. The gear- 100 wheel 28 is secured on the outer end of the shorter parallel shaft 34, which is mounted to rotate in suitable bearings 35 and 36, formed in the pillars 21 and 22 beneath the bearings 30 and 31. Between the bearings 105 35 and 36 the gear-pinion 37 is secured on the shaft 34 and meshes with a gear-wheel

38, rigidly secured upon the shaft 29. From a consideration of the above-described gear mechanism it will be seen that power which is applied to the belt-wheel 25 is transmitted 5 at reduced speed to the shaft 34 and is thence in turn transmitted to the shaft 29, which is shown as arranged to make one revolution for every four revolutions of the shaft 34, the gear-wheel 38 having four times as many 10 teeth as the pinion 37. The sleeve 26, rotating in the same direction as the shaft 29, although at a higher rate of speed, does not create as much friction on said shaft as it would if the parts were rotating in opposite 15 directions. Secured upon the other end of the shaft 29, between the pillars 22 and 23, is the forming wheel or disk 39, which has the elongated hub 40, the comparatively thin web 41, and the forwardly-extending peripheral flange 42, the whole constituting a cup-shaped disk. Secured to the periphery of the wheel 39 on the opposite side from the flange 42 is the gear-flange 43, which meshes 20 with a gear-pinion 44, secured rigidly to or formed integrally with the can-body-forming cylinder or sleeve 45, the size of the gear-wheel or flange 43 and the pinion 44 being so regulated that each revolution of the wheel 39 will cause eight revolutions of the cylinder 45. To keep the wheel 42 and the cylinder 45 in exact alinement, as well as to 25 form an edge-guide for the blanks, I form on the peripheral flange 42 of the wheel 39 a rib 46, which engages a correspondingly-shaped annular groove or channel 47 formed in the cylinder 45. The cylinder 45 is mounted to 30 rotate on the stationary bearing-shaft 48, which is secured in suitable bearings 49 and 50, formed in the pillars 21 and 22 the necessary distance above the bearings 30 and 31.

Premising that the can-bodies are formed on the cylinder 45 in the same general manner as shown in the aforesaid application, Serial No. 101,838, the can-bodies with the hooks completed are shoved off of the cylinder 45 at the end of each second revolution by the discharge-collar 51, which, as shown in Fig. 9, extends around so much of the cylinder 45 as is possible without interfering 40 with its coöperation with the wheel 39. The bearing portion of the inner periphery of the sleeve 51 fits snugly upon the cylinder 45 and has formed therein the offset 52, which normally rests in the same plane as the outer 45 edge of the flange 46, so that when the discharge-sleeve 51 is shoved to the right, as indicated in dotted lines in Fig. 4, the can-body will be shoved thereby onto the horn 53, which is secured to the end of the bearing-shaft 48 and supported thereby in the same 50 manner as fully shown and described in my aforesaid application, Serial No. 101,838. To reciprocate the discharge-sleeve 51 at the proper intervals, I connect it by the rods 54 (best shown in Fig. 3) with the ears 55,

formed on the sleeve 56, which has the lugs 57 on either side thereof taking into the slightly-elongated slots 58, formed in the ends of the arms or levers 59, connected by the spacing-sleeve and rod 60 and by the 70 rock-shaft 61, which is mounted in the elongated bearing 62, formed in the bearing-sleeve 63 on the shaft 29, between the gear-wheel 38 and the pillar 22, to which it is attached, as by the screw 64. The lower end 75 of one of the arms or levers 59 has placed thereon in the plane of the shaft 34 a bearing-pin or antifriction-roller 65, which takes into the cam-groove 66, formed in the cam-wheel 67, secured upon the shaft 34 between 80 the pinion 37 and the bearing 36. The cam-groove 66 is so shaped as to give the collar 56, and consequently the sleeve 51, a rapid reciprocation back and forth during a portion of every alternate revolution of the cylinder 45 and at the proper time to discharge 85 the can-body therefrom.

The can-body, with the locked seam formed but not pressed, is delivered onto a horn 53, whence it is carried by the chains 68 through 90 the seam-pressing mechanism, (designated generally by the reference character 69,) which will not be described in detail, as it is the same as shown in my aforesaid application, Serial No. 101,838. The chains 68 are 95 operated by the sprocket-wheels 70, secured on the upper ends of the vertical shafts 71, mounted in the vertical bearing-sleeves 72, forming a part of the bracket 73, which is secured to the pillar 23 between it and the pillar 22. The shafts 71 have the bevel gear-pinnions 74, secured on the lower ends thereof and meshing with the oppositely-disposed bevel gear-wheels 75, secured on the shaft 76, mounted to rotate in the bearings 77, secured on the lower ends of the arms 78, projecting downward from the bearing-sleeves 72 and forming a part of the bracket 73. Motion is given to the shaft 76 by means of a bevel gear-wheel 79, secured on the end of 105 the shaft 29 and meshing with the bevel gear-pinion 80, secured on the shaft 76. Secured to one end of the shaft 76 is the sprocket-wheel 81, which by means of the sprocket-chain 82, meshing with the sprocket-wheel 110 83, secured on the shaft 84, operates the seam-pressing mechanism in the customary manner and at the proper rate of speed. Of course it will be understood that the gear mechanism just described serves to operate 115 the chains 68 at the proper rate of speed to bring a pair of the lugs 85 thereon forward at the proper intervals to receive the can-bodies as they are discharged onto the horn 53 by the sleeve 51 and carry them through the seam-pressing mechanism and onto the soldering mechanism, which is not shown.

The forming-cylinder 45 has extending longitudinally thereof from the outer end to the channel 47 a seam-forming groove 86, 130

which, as best shown in Figs. 11 and 12, is of the proper size and shape to receive the edges of the tucking-blades 87 and 98, of which there are four pairs equidistantly disposed in the flange 42, which is formed with the enlargements 88 on the inner side thereof to form the housings for the tucking-blades, the operating edges of which are of the same length as the width of the flange 42, the lower portion of which, however, is reduced sufficiently to permit the fastening of the covering-plates 89 on the outer surface of the enlargements 88 to hold the tucking-blades in place after they have been inserted in the slots 90, formed in the enlargements 88 to receive them. Adjacent to the slot 90 and running into it, as seen in Fig. 5, is a pair of recesses 91, which have their lower ends closed by plugs 92 and which receive the correspondingly-shaped lugs 93 secured to the blades 87 and 98, above which are placed the helically-coiled expanding-springs 94, which tend to hold the tucking-blades in their lowermost position with their operative edges either flush with or below the surface of the flange 42. The seam-forming groove 86 is placed at a slight angle to the surface of the forming-cylinder 45, and the tucking-blades 87 are set at the same angle.

Premising that before each of the tucking-blades 87 comes into operative engagement with the groove 86 a blank 95 has been placed on the flange 42 at the right position, it will be seen that as the disk 39 rotates to the proper position to bring a tucking-blade 87 into engagement with the groove 86 the lower end of the blade engages with the cam-surface 96, which is formed on the cam-block 97, secured upon the rearward extension 98^a of the bracket 73, so that as the groove 86 comes directly beneath the axis of the cylinder the operative edge of the first tucking-blade 87 of a pair is forced completely into the groove forming the first hook on the blank, the thickness of the loop of tin and of the edge of the tucking-blade practically filling the groove. Just at the instant the hook is completely formed the end of the tucking-blade passes over the highest point of the cam-block 97 and the blade is forced back by the action of the springs 91 and of the edge of the groove 86. The hook thus formed on the edge of the blank 95 is fastened firmly in the groove 86, so that as the rotation of the cylinder 45 continues the blank 95 is wrapped about the cylinder and any tendency that it might have to spring away from it is prevented by the edge of the discharge-collar 51, which extends over the blank. At the end of the complete rotation of the forming-cylinder 45 the other end of the blank 95 extends across the recess 86 just far enough to be pushed into it by the operating edge of one of the four equidistant tucking-blades 98, constituting the second members of the pairs and which correspond

in every respect to the intermediate tucking-blades 87, the first members of the pairs, except that the operative edge is narrower than the operative edge of a tucking-blade 87 by an amount equal to the thickness of the sheet of tin being operated on. By the mechanism thus described it will be apparent that if the blanks are properly fed to the machine there will be four complete can-bodies formed at each revolution of the forming-wheel 39 and discharged onto the soldering-horn.

As a means of accurately feeding the blanks with but little care I provide the mechanism to be described. Secured upon the side of the pillar 22, as by the cap-screws 99, is a bracket 100, which consists of the substantially segmental plate 101, which is shown as extending through something over ninety degrees and which is provided with a forwardly-projecting flange on its upper edge 85 and consists of the short horizontal part 102, the vertical part 103, and the circular part 104. The general outlines of the inner surfaces of the parts 103 and 104 vary somewhat for the following purposes: The sheet 90 or blank 95 is intended to be thrust into the recess formed between the vertical flange 103 and the periphery of the flange 42 and upon the horizontal part 102 while it is standing vertically upon one end, and the upper and lower inner portions of the flange 103, as at 105, are flared outwardly from the inner reduced portion 106, so that the blank 95, which is pushed into the recess vertically, will be bent by contact with the surfaces 105 100 into a curve corresponding to the curve of the periphery of the flange 42, and when thus bent its inner edge will be caught under the reduced portion 106, so that the blank will be carried forward in the curved position. To 105 catch the end of the blank and carry it forward, I provide in the reduced spaces 107, formed on the surface of the flange 42 between the alternate enlargements 88, a pair of leaf-springs 108, which are slotted at their 110 rear ends, (as seen in Fig. 7,) so that they can be adjustably secured by the set-screws 109 in order to bring their upwardly-turned ends 110 into just the proper position to catch the rear edge of the blank and carry it forward, 115 so that its ends will be in the exact position necessary for the formation of the hooks by the mechanism previously described. The surface of the reduced portions 107 beneath the forward ends of these springs 108 is depressed, forming the channels 111, into which the main portion of the bodies of the springs 108 can sink, as is necessary when the operative ends 110 pass beneath the cylinder 45, as seen in Fig. 12. The reduced portion 120 106 of the under surface of the flange of the bracket 100 extends forward beneath the portion 104, and the portion 112 of the under surface of the flange 104 directly adjacent the vertical portion 103 of the flange is brought 130

downward at an angle, as shown, so that at 113 the reduced portion 106 may be described as extending entirely across the flange. The channel formed between the 5 flange 104 and the periphery of the flange 42 from 113 to the point where the blank is delivered to the roller 45 is, except for the sockets for the rollers, to be hereinafter mentioned, all reduced, so that the sheet cannot 10 possibly escape from the ends 110 of the springs 108, which contact with the under surface of the flange 104, which forms a continuation of the reduced portion 106. By the mechanism thus described it will be seen 15 that if a blank 95 be thrust into the recess in advance of the rising of the operating ends 110 of the springs 108 through the recesses 102^a in the flange 102 the blank will be caught by said springs and carried forward to the 20 forming-cylinder 45.

To hold the blank firmly upon the periphery of the cylinder and to keep it exactly in position, I preferably provide a plurality of spring-pressed rollers 114, which are journaled in yokes 115, mounted to slide in suitable recesses 116, formed in the thickened portion 104 of the flange of the bracket 100. The yokes 115 have the stems 117 extending radially through the brackets 118, projecting 25 from the periphery of the flange 104, and by interposing the helically-coiled expanding-spring 119 between the top of the bracket 118 and the set-nut 120, screwed onto the lower portion of the stem 117, I am enabled 30 to vary the pressure of the wheels or rollers 114 on the periphery of the flange 42 to any desired extent. These rollers effectually prevent the blank from bending or buckling as it is being fed to and around the cylinder 45. 35 To insure the blank being fed squarely against the flange 46, so that its edges will be exactly square across the line of travel to make the hooks, I provide the guide-rollers 121, which are preferably mounted on vertical spindles extending downward from the brackets 122, formed on the edge of the flange 104, in position, so that the rollers 121 rest practically against the edge of the flange 42 and against the edge of the blank, which 40 is, as above stated, of the same width as the flange 42 outside of the guide-rib 46.

It will be apparent that the sheets may be thrust by hand into the above-described feeding apparatus; but in order to arrange for the 45 automatic feeding of the sheets, so as to make a higher speed of the machine possible, I provide the automatic mechanism best shown in Figs. 1 to 3, 6 and 7. Secured to the base-plate 20 is a bracket 123, which has a comparatively short upwardly-extending portion 124, terminating in the bearing-sleeve 125, in which is mounted one end of the short horizontal shaft 126, the other end of which is mounted in a bearing 127, formed on the 50 forward face of the pillar 23. This shaft 126

has secured thereon the sprocket-wheel 128, which through the sprocket-chain 129 is driven by the large sprocket-wheel 130, secured on the shaft 76. The outer end of the shaft 126 has secured thereon the cam-disk 70 131, which has formed therein the cam-groove 132, co-operating with the bearing pin or roller 133, secured in the rocking arm or lever 134, which is pivoted at its lower end on the bearing-stud 135, projecting outwardly 75 from the casting 123. The upper end of the lever 134 has the slightly-elongated slot 136 therein, through which passes the pin or stud 137, secured to the blank-feeding slide 138, which is mounted to reciprocate horizontally on the dovetailed bearing-way 139, formed on the other portion 140 of the bracket 123, which extends vertically upward to a height somewhat above the vertical portion 103 of the bracket 100. This delivery-slide 80 138 is adapted to strike the side edges of the blanks as they are presented to it one by one in a vertical position and to drive them into the receiving-pocket formed in the bracket 100. As will be seen from Fig. 2, the 85 discharge-slide 138, and especially the contacting end thereof, is made of a plano-concave shape in cross-section, so that as the blanks are curved in passing into the pocket they will not escape from the operating end 90 of the discharge-slide. The upper portion of the bracket 140 is formed with a plurality, preferably four, of bearings 141, which are suitably disposed to receive the screw-shafts 142, which have their other ends mounted 95 to rotate in the oppositely-disposed bearings 143 formed in the companion bracket or side 144, which is spaced apart from and rigidly secured to the bracket 140 by means of the interposed bracket 145 at the bottom 100 thereof and the bar 146 at the top. These screw-rods 142, where four are employed, are so located that the uppermost and lowermost ones engage the tops and bottoms of a bundle 105 of the blanks 95 that may be placed in the 110 discharge mechanism, while the intermediate ones engage with the sides of the blanks that are presented to the feeding-plate 138. These shafts all have the small sprocket-wheels 147 secured to the inner ends thereof and are all 115 connected by the sprocket-chain 148, which rotates them in unison in the same direction, power being conveniently applied to them by the additional sprocket-wheel 149, secured to the inner end of the lowermost shaft 142 and 120 connected by the sprocket-chain 150 with the driving sprocket-wheel 151, secured on the outer end of the shaft 76. As will be seen from an examination of Fig. 2, the outer ends 125 of the screw-rods 142 have the threads formed thereon of a uniform pitch and preferably as nearly as possible of the same number of threads to the inch as there are sheets of tin in a pile an inch high. It will be apparent that it would be impossible to feed the blanks 130

one at a time to the machine by the reciprocating slide 138 unless they were separated, and for this purpose the inner portions of the screw-rods are formed with a constantly-diminishing number of threads to the inch, so that while the blanks are placed therein close together they will be spread apart as they are carried toward the machine by the rotation of the screw-rods, so that when they reach the discharge-point they will be separated far enough so that the discharge-plate 138 can catch one of the blanks and force it into the machine and retreat before the adjacent blank interferes and is presented to the proper point to be operated on in turn. The blanks are placed into the feeding mechanism in bunches at the outer portion thereof, and to hold them in place to be operated on by the intermediate screws as well as the top and bottom screws I secure the substantially U-shaped bar 152 to the bracket 145 and the cross-piece 146 and secure on the inner face thereof two or more bars 153, having their outer ends beveled slightly to catch the blanks if they may be projecting out a little bit and force them inwardly into engagement with the intermediate screws 142 and hold them in engagement until they reach the discharge-point.

By the employment of the feeding mechanism described it will be apparent that the operator has only to place the sheets or blanks into the feeding apparatus a bunch at a time and that they will be spread out and delivered to the machine as rapidly as it can take care of them. By the employment of this feeding mechanism I make possible a higher rate of operation for the machine than can be obtained where the feeding is done by hand one blank at a time.

While I have shown and described the pair of reciprocating tucking-blades mounted in a rotating cylinder, I contemplate employing blades which do not move relative to the surface of the cylinder or the other member coöperating with the mandrel, and, furthermore, I contemplate employing a pair of tucking-blades coöperating alternately with the seaming-groove of the mandrel whether said mandrel be rotatable or stationary, irrespective of and apart from the cylinder, so that I do not desire to be limited to the form shown.

While I have shown my invention as embodied in the form which I at present consider best adapted to carry out its purposes, it will be understood that it is capable of modifications and that I do not desire to be limited in the interpretation of the following claims, except as may be necessitated by the state of the prior art.

What I claim as new, and desire to secure by Letters Patent of the United States, is—

1. In a device of the class described, the combination with the roller having the seam-

ing-groove therein, of the coöperating roller having a pair of tucking-blades therein coöperating alternately with the seaming-groove, and means for rotating said rollers in synchronism.

2. In a device of the class described, the combination with the roller having the seaming-groove therein, of the coöperating roller having a pair of tucking-blades therein coöperating alternately with the seaming-groove and having their engaging edges of different sizes for the purpose described, and means for rotating said rollers in synchronism.

3. In a device of the class described, the combination with the roller having the seaming-groove therein, of discharge mechanism for carrying the can-body off of said roller, the coöperating roller having a pair of tucking-blades therein coöperating alternately with the seaming-groove, a portion of the periphery of the second roller between the blades being reduced to facilitate the discharge of the cans from the roller, and means for rotating said rollers in synchronism.

4. In a device of the class described, the combination with the roller having the seaming-groove therein, of the tucking-blade roller whose circumference is a multiple of that of the grooved roller, means for rotating said rollers at the same peripheral velocity, and plural pairs of tucking-blades coöperating with said seaming-groove.

5. In a device of the class described, the combination with the roller having the seaming-groove therein, of the tucking-blade roller whose circumference is a multiple of that of the grooved roller, means for rotating said rollers at the same peripheral velocity, plural pairs of tucking-blades coöperating with said seaming-groove, and discharge mechanism coöperating with the grooved roller to discharge a can-body therefrom at every second rotation thereof, said tucking-blade roller having the reduced portions on the periphery thereof located so as to be opposed to the grooved roller while the cans are being discharged therefrom.

6. In a device of the class described, the combination with the roller having the seaming-groove therein, of the tucking-blade roller whose circumference is a multiple of that of the grooved roller, means for rotating said rollers at the same peripheral velocity, plural pairs of tucking-blades coöperating with said seaming-groove, discharge mechanism coöperating with the grooved roller to discharge a can-body therefrom at every second rotation thereof, said tucking-blade roller having the reduced portions on the periphery thereof located so as to be opposed to the grooved roller while the cans are being discharged, and fingers upon the periphery of the tucking-blade roller adapted to engage with blanks and carry them to the grooved roller properly positioned upon the unreduced por-

tion of the periphery of the tucking-blade roller.

7. In a device of the class described, the combination with the roller having the seaming-groove therein, of the tucking-blade roller whose circumference is a multiple of that of the grooved roller, means for rotating said rollers at the same peripheral velocity, plural pairs of tucking-blades coöperating with said seaming-groove, discharge mechanism coöperating with the grooved roller to discharge a can-body therefrom at every second rotation thereof, said tucking-blade roller having the reduced portions on the periphery thereof located so as to be opposed to the grooved roller while the cans are being discharged, and adjustable mechanism on the periphery of the tucking-blade roller adapted to engage with the blanks and carry them to the grooved roller properly positioned upon the unreduced portion of the periphery of the tucking-blade roller, said mechanism consisting of the radially-extended fingers attached to the circumferentially expanding and adjustable spring bodies mounted in said reduced portions of the periphery of the tucking-blade roller above suitable depressions therein.

8. In a device of the class described, the combination with the roller having the seaming-groove therein, of the coöperating tucking-blade roller carrying a pair of tucking-blades and adapted to receive blanks upon its periphery and carry them to the grooved roller, and means for rotating said rollers at the same peripheral velocity.

9. In a device of the class described, the combination with the roller having the seaming-groove and the annular channel therein, of the coöperating tucking-blade roller having the flange coöperating with said annular channel and carrying a pair of tucking-blades and adapted to receive blanks upon its periphery and carry them to the grooved roller, and means for rotating said rollers at the same peripheral velocity.

10. In a device of the class described, the combination with the roller having the seaming-groove and the annular channel therein, of the coöperating tucking-blade roller carrying the pair of tucking-blades adapted to co-operate with the seaming-groove and having the flange on its periphery coöperating with the annular channel and adapted to receive blanks upon its periphery and carry them to the grooved roller, means for rotating said rollers at the same peripheral velocity, and means for holding a blank against the flange as it is carried to the grooved roller.

11. In a device of the class described, the combination with the roller having the seaming-groove and the annular channel therein, of the coöperating tucking-blade roller carrying the pair of tucking-blades adapted to co-operate with the seaming-groove and having

the flange on its periphery coöperating with the annular channel and adapted to receive blanks upon its periphery and carry them to the grooved roller, means for rotating said rollers at the same peripheral velocity, and means for holding a blank against the flange as it is carried to the grooved roller consisting of the plurality of rollers journaled in the frame so as to bring their peripheries against the edge of the tucking-blade roller and the blank, the opposite edge of the blank resting against the flange.

12. In a device of the class described, the combination with the roller having the seaming-groove and the annular channel therein, of the coöperating tucking-blade roller carrying the pair of tucking-blades adapted to co-operate with the seaming-groove and having the flange on its periphery coöperating with the annular channel and adapted to receive blanks upon its periphery and carry them to the grooved roller, means for rotating said rollers at the same peripheral velocity, and means for holding a blank against the flange as it is carried to the grooved roller consisting of the plurality of rollers journaled in the frame on axes set at acute angles to the periphery of the tucking-blade roller so as to bring their peripheries against the edge of the tucking-blade roller and the blank, the opposite edge of which rests against the flange.

13. In a device of the class described, the combination with the roller having the seaming-groove therein, of the coöperating tucking-blade roller carrying a pair of tucking-blades and adapted to receive blanks upon its periphery and carry them to the grooved roller, and the spring-pressed rollers coöperating with the periphery of the tucking-blade roller to hold the blank firmly in engagement therewith as it is fed to the grooved roller.

14. In a device of the class described, the combination with the roller having the seaming-groove therein, of the coöperating tucking-blade roller carrying a pair of tucking-blades and adapted to receive blanks upon its periphery and carry them to the grooved roller, the spring-pressed rollers coöperating with the periphery of the tucking-blade roller to hold the blank firmly in engagement therewith as it is fed to the grooved roller, and means for adjusting the tension of the springs.

15. In a device of the class described, the combination with the roller having the seaming-groove therein, of the tucking-blade roller carrying a pair of tucking-blades and adapted to receive blanks upon its periphery and carry them to the grooved roller, means for rotating said rollers at the same peripheral velocity, a pair of fingers projecting from the periphery of the tucking-blade roller near its edges and just back of the second tucking-blade, and the spring-pressed rollers coöperating with the pe-

riphery of the tucking-blade roller between the fingers to hold the blank in engagement therewith.

16. In a device of the class described, the combination with the blank-receiving roller, of the shield therefor adapted to bend a blank to the curve of the roller as it is thrust sideways between said roller and shield.

17. In a device of the class described, the combination with the blank-receiving roller, of the shield therefor adapted to bend a blank to the curve of the roller as it is thrust sideways between said roller and shield, and fingers on said roller adapted to catch the end of the blank and carry it forward between the shield and the roller.

18. In a device of the class described, the combination with the blank-receiving roller, of the shield therefor adapted to bend a blank to the curve of the roller as it is thrust between said roller and shield, said shield having its inner surface on substantially the same curve as the periphery of the blank-receiving roller and extending closely thereto and having a portion of its outer surface of a length equal to a blank on a straight line and curved inwardly to meet the curved inner portion thereof, and fingers on said roller adapted to catch the end of the blank and carry it forward between the shield and the roller; substantially as shown and described.

19. In a device of the class described, the combination with the blank-receiving roller, of the shield therefor adapted to bend a blank to the curve of the roller as it is thrust between said roller and shield, and automatic mechanism for thrusting blanks one by one between said shield and roller.

20. In a device of the class described, the combination with the blank-receiving roller of the shield therefor adapted to bend a blank to the curve of the roller as it is thrust between said roller and shield, automatic mechanism for thrusting blanks one by one between said roller and shield, and means for driving said roller and automatic mechanism in synchronism.

21. In a device of the class described, the combination with the blank-working mechanism, of a blank-feeding mechanism operating in synchronism therewith and including a plurality of screws of increasing pitch adapted to feed forward and separate the blanks, and means for rotating the screws in unison.

22. In a device of the class described, the combination with the blank-working mechanism, of a blank-feeding mechanism operating in synchronism therewith and including a plurality of screws of increasing pitch adapted to feed forward and separate the blanks, means for rotating the screws in unison, and a reciprocating plunger adapted to discharge the blanks one by one from said screws to the blank-working mechanism after they are separated.

23. In a device of the class described, the combination with the blank-working mechanism, of a blank-feeding mechanism operating in synchronism therewith and comprising a blank-receiving cage open at one side having screws of increasing pitch in the opposite side and in the top and bottom of the cage, means for rotating the screws in unison, and a reciprocating plunger adapted to discharge the blanks one by one from said screws to the blank-working mechanism after they have been separated. 70

24. In a device of the class described, the combination with the blank-working mechanism, of a blank-feeding mechanism operating in synchronism therewith and including a plurality of screws of increasing pitch adapted to feed forward and separate the blanks, means for rotating the screws in unison, a reciprocating plunger adapted to discharge the blanks one by one from said screws to the blank-working mechanism after they are separated, a shaft rotating in unison with the screws, and connections between the shaft and plunger to reciprocate it once during a portion of each rotation of the screws. 80

25. In a device of the class described, the combination with a stationary journal supported at one end and having the horn secured to the other end thereof, of the grooved roller journaled thereon, a parallel shaft carrying the tucking-blade roller in the plane of the grooved roller, gearing connecting said rollers to compel them to rotate at the same peripheral velocity, and discharge mechanism 95 cooperating with the grooved roller at every other rotation thereof.

26. In a device of the class described, the combination with the stationary journal supported at one end and having the horn secured to the other end thereof, of the grooved roller journaled thereon, a parallel shaft carrying the tucking-blade roller in the plane of the grooved roller, gearing connecting said rollers to compel them to rotate at the same 100 peripheral velocity, discharge mechanism 105 cooperating with the grooved roller at every other rotation thereof, a parallel cam-shaft, connections between said cam-shaft and discharge mechanism for operating the same, 110 and gearing between said shafts for operating them at the proper relative speeds. 115

27. In a device of the class described, the combination with the stationary journal 48 supported at one end, of the grooved roller 120 45 journaled thereon, a parallel shaft 29 having the pulley-wheel 25 loosely mounted on the outer end thereof and the tucking-blade roller secured on the inner end thereof in the plane of the grooved roller, discharge mechanism 125 reciprocating on the journal 48 and cooperating with the grooved roller 45 at every other rotation thereof, the parallel cam-shaft 34 having the cam thereon, the operating-lever connecting the cam and the discharge 130

mechanism, and the train of gearing substantially as shown and described connecting the pulley-wheel 25 with the shaft 29 through the shaft 34.

5 28. In a device of the class described, the combination with the roller having the seaming-groove therein, of the coöperating roller having a pair of tucking-blades therein coöperating alternately with the seaming-groove, 10 means for operating said tucking-blades, and means for rotating said rollers in synchronism.

29. In a device of the class described, the combination with the roller having the seaming-groove therein, of the coöperating roller having a pair of tucking-blades therein coöperating alternately with the seaming-groove and having their engaging edges of different sizes for the purpose described, means for operating said tucking-blades, and means for rotating said rollers in synchronism.

30. In a device of the class described, the combination with the roller having the seaming-groove therein, of discharge mechanism 15 for carrying the can-body off of said roller, the coöperating roller having a pair of tucking-blades therein coöperating alternately with the seaming-groove, a portion of the

periphery of the second roller between the blades being reduced to facilitate the discharge of the cans from the roller, means for operating said tucking-blades, and means for rotating said rollers in synchronism. 30

31. In a device of the class described, the combination with the forming-horn having the seaming-groove therein, of the pair of tucking members adapted to coöperate alternately with the groove, and means for moving the members to alternately enter the groove. 35

32. In a device of the class described, the combination with the forming-horn having the seaming-groove therein, of the pair of tucking members adapted to coöperate alternately with the groove and having their 40 engaging edges of different form, and means for moving the members to alternately enter the groove.

In testimony whereof I have hereunto affixed my signature, this 4th day of June, 50 1902, in the presence of two witnesses.

JOHN HOWARD McELROY.

Witnesses:

GEORGE R. HARBAUGH,
ROBERT K. GUSTAFSON.
